UNITED STATES PATENT OFFICE.

ARTHUR O. ULLREY, OF NILES, MICHIGAN.

SPRING-CATCH FOR POLE-TIPS.

SPECIFICATION forming part of Letters Patent No. 619,638, dated February 14, 1899.

Application filed December 12, 1898. Serial No. 699,037. (No model.)

To all whom it may concern:

Be it known that I, ARTHUR O. ULLREY, of Niles, in the county of Berrien and State of Michigan, have invented certain new and useful Improvements in Spring-Catches for Pole-Tips; and I hereby declare that the following is a full, clear, and exact description thereof, reference being had to the accompanying drawings, which form part of this specification.

This invention is an improved spring-catch for use on the poles of carriages and wagons to retain the neck-yoke in position thereon; and it consists in the construction and combination of parts illustrated in the accompanying drawings and hereinafter described.

Referring to said drawings, Figure 1 is a longitudinal vertical section through a pole-tip provided with my improved spring-catch. Fig. 2 is a transverse section on line 2 2, Fig. 1. Fig. 3 is a detail view of the spring-catch. Fig. 4 is a detail perspective view of the end of the pole.

B designates the pole of a carriage, and A designates the iron tip, which is usually placed on the end thereof and which is provided with a collar a, against which the neck-strap presses.

The pole B has a short vertical socket b for the accommodation of the end c of the spring C and a longitudinal groove b' in its lower side, extending from its socket to its frontend, in which is a short vertical groove b², connecting groove b' with a longitudinal upper groove b³ in the upper side of the pole, as shown, these grooves b' b² b³ being adapted to accommodate parts of the latch-spring C. This spring is bent almost into rectangular form, having an upper portion c³, which fits into the groove b³, a vertical portion c², fitting in groove

b², and a lower portion c', adapted to fit in groove b'. The rear end of part c' is bent downward, so as to normally project below the pole, and the front end c of the spring is vertical and adapted to enter socket b and provided at its upper end with a lip c⁴, which is adapted to catch on the lower wall of the iron tip A, as shown, said tip being provided with a slot a² just below slot D' in the pole, through which the hook portion c of the spring normally projects.

The pole B is socketed and grooved, as described. Then the spring C is slipped into

place by engaging its portions c' c² c³ with the grooves b' b² b³. Then the iron tip A is driven over the end of the pole and the spring, first forcing the portion c of the spring up into the socket b and groove b' until the tip A is driven onto the pole sufficiently to permit the part c to spring out through the slot a². In this position the spring is rigidly secured in place, and the construction is simple, efficient, and convenient. The neck-yoke is slipped over the tip in the usual manner until it strikes the collar a, and in doing so the yoke-ring will of course force spring-catch c into the socket until the ring passes the catch, when the latter springs outward and will hold the neck-yoke firmly upon the tip.

The spring-catch as thus constructed will also assist in holding the tip A in place should it become loosened; but of course the tip A should be provided with other fastening devices. The shape of the spring and the arrangement of the grooves into which it fits insure the maintenance of proper relation between the spring and the pole at all times.

Having thus described my invention, what I therefore claim as new, and desire to secure by Letters Patent, is—

1. The combination of the pole provided with a socket, and longitudinal and end grooves substantially as described, and a spring having a catch portion adapted to engage the socket and other portions fitting in the grooves of the pole; with a metal tip fitted over the pole and spring, and holding the latter securely in place in the grooves of the pole, and provided with a slot through which the latching portion of the spring normally projects, for the purpose and substantially as described.

2. The combination of the pole, having top, bottom and end grooves substantially as described, the spring fitted into said grooves and having its lower leg bent into a spring-catch, and a metal tip fitted over the pole and spring, and confining the latter in the grooves of the pole, and provided with a slot through which the latch portion of the spring projects.

3. The combination of the pole having a vertical slot or socket b, top and bottom longitudinal grooves b', b³, and an end groove b²; and a spring having top, bottom and end portions c', c², c³, fitting in the grooves b', b², b³,

respectively, and also having a spring-catch portion c^4 provided with a lip c^4 adapted to enter the socket b ; and a metal pole-tip A fitted over the end of the pole and securing the
5 spring in position thereon and provided with a slot a^3 through which the catch portion of the spring projects, substantially as described.

In testimony that I claim the foregoing as my own I affix my signature in presence of two witnesses.

ARTHUR O. ULLREY.

In presence of—

PAUL SKALLA,

COLONEL F. BOND.
